AMINOESTERS OF N-SUBSTITUTED PYRROLIDINE 2,5-DICARBOXYLIC ACIDS

Arthur Joseph Hill, Jr., and John Thomas Maynard, Wilmington, Del., assignors to American Cyanamid Company, New York, N. Y., a corporation of Maine

No Drawing. Application December 28, 1946,
Serial No. 719,108

5 Claims. (Cl. 260—326.3)

1

This invention relates to a new and novel method of preparing N-substituted pyrrolidine carboxylic acids and esters thereof and to a new and novel group of esters so produced. More particularly, this invention relates to a novel group of alkamine esters of N-substituted pyrrolidine 2,5-dicarboxylic acids, to the alkamine esters so produced and to the salts of these esters.

In the discussion and disclosure of the present invention the pyrrolidine ring has been considered as the conventionally designated

group.

Comment has been made on the frequent occurrence of pyrrolidines in nature. The pyrrolidine nucleus is found in many naturally-occurring products. Particular illustrations include physiologically-active alkaloids such as those of the hygrine, belladonna and tobacco families and the important natural aminoacid, proline. Various pyrrolidine carboxylic acids are frequently found in these and similar compounds, or in degradation products thereof.

It is to be noted, however, that in the compounds derived from nature the heterocyclic nitrogen in the pyrrolidine nucleus is usually either unsubstituted or is substituted only by methyl. Despite the biochemical significance of the pyrrolidines, surprisingly little is known in the prior art about compounds such as the pyrrolidine dicarboxylic acids. Particularly is this true when there is an N-substituent other than methyl, where the carboxylic group or groups is esterified. In large part, this has been due to a lack of a good synthesis for pure compounds of this type and, therefore, also to the previous lack of such compounds for investigation.

It is, therefore, a principal object of the present invention to develop a synthesis which is comparatively simple, which is reliable, which yields easily-purified products and which can be adapted to the production of a wide range of such compounds. It is also an object of the invention to produce a number of novel N-substituted pyrrolidine carboxylic acids and these esters, particularly the alkamine esters of such acids.

The objects of the present invention have been met by the production of a number of alkamine esters of N-substituted pyrrolidine 2,5-dicarboxylic acids. In general, these compounds have been synthesized by ring-closing a suitable lower

2

alkyl diester of an alpha,delta dihalogenated adipic acid with a suitable amine, usually a primary amine, preferably in the presence of a suitable catalyst, and then conducting a catalyzed ester interchange whereby the alkamine radical is substituted for the alkyl.

Adipic acid, alpha,delta-dihalogenated adipic acids, and even the alkyl esters of such acids are known. The process of the present invention, therefore, originates with known compounds of the type

in which Al and Al' represent the same or different alkyl radicals and Hal represents a halogen.

While Al and Al' may differ, and may have any desired number of carbon atoms, for the present procedure they will usually be identical. While they may also be of any reasonable chain length, those longer than butyl are too long and of no particular importance in the present synthesis. On economical considerations both Al and Al' are usually either methyl or ethyl. Of the two, because of the extremely hygroscopic nature of the dimethyl ester of pyrrolidine 2,5-dicarboxylic acid, ethyl is usually preferable.

As noted, Hal may designate any halogen. Practically, however, only chlorine and bromine are ordinarily encountered. For purposes of the synthesis, bromine is preferable and the further discussion will be limited thereto as illustrative.

It should be noted that the alkyl dibromo-adipates, in which the alkyl groups are identical, may occur in several forms because of asymmetry. While other forms may be used, in the present work the meso form has been principally used to insure formation of a definite product.

While these compounds are known, their preparation for the present purpose may be illustrated by the following procedure.

EXAMPLE 1

45 Meso ethyl alpha, delta-dibromo adipate

Adipyl chloride is placed in a quartz flask equipped with reflux condenser and dropping funnel. The flask is continuously subjected throughout the reaction to irradiation by ultra violet light. To the adipyl chloride is added drop-wise bromine in amount sufficient to total about 2.25 moles per mole of adipyl chloride. When reaction appears complete, the mixture is gently

heated until excess bromine is removed and evolution of hydrogen bromide ceases. The residue, alpha, delta dibromo adipyl chloride, is slowly added with agitation to absolute ethyl alcohol. As soon as the reaction becomes violent, the reaction vessel is cooled. The reaction mixture is allowed to stand for about twenty-four hours and seeded, being then allowed to stand in the cold until crystallization substantially ceases. The white crystalline ester is removed by filtration, washed with cold ethyl alcohol and vacuum dried. Two successive crystalline products are obtained in further standing in the cold. These products are in the meso form. Alcohol is distilled from the residue, yielding another crop of solid esters and a liquid phase. The liquid phase appears to comprise dl diethyl alpha,delta-dibromoadipate together with a small amount of alpha, alpha-dibromoadipate. The solid crystalline ester so produced has a melting point of 66-67° C. which checks with that ascribed in published literature.

EXAMPLE 2

Meso methyl alpha, delta-dibromoadipate

This compound is prepared by substituting absolute methyl alcohol for the ethyl alcohol of the preceding experiment. The solid meso methyl ester is readily soluble in benzene, chloroform, acetone or ether, moderately soluble in ethyl alcohol, difficultly soluble in petroleum ether and insoluble in water. Crystallization from petroleum ether yields long, colorless needles, from alcohol, large colorless, elongated prisms. The solid ester has a melting point of 75-76° C.

Using the above procedures as illustrative, any alkyl ester in which the alkyl groups are identical may be prepared. As noted above, only the methyl, ethyl and possibly propyl are of any practical significance in the present process, largely because of the economic considerations.

Starting with a dialkyl dibromoadipate, the reaction of the present synthesis may be considered as falling into two stages, a ring closure and an alcoholysis, capable of representation by the following:

in which Al is an alkyl radical, R is the residue of a suitable amine and Alk is the residue of a tertiary aminoalcohol.

In the above formula RNH₂ has been used to designate a suitable primary amine. In the reaction R may be quite widely varied. It may represent a simple alkyl radical of from 1-12 carbon atoms; a substituted alkyl radical such as methoxymethyl, ethoxymethyl, ethoxyethyl, methoxypropyl, cyclohexylethyl, and the like; an aminoaliphatic radical such as aminoethyl, acetylaminooethyl and the like; a cycloaliphatic radical such as cyclohexyl, ethyl and methylcyclohexyl and the like; an aryl radical such as phenyl, o,m- or p-tolyl, p-chlorophenyl, 2,4-dimethylphenyl, 3,5-dimethyl phenyl, ethyl phenyl, eth-

oxy phenyl, methoxyphenyl, acetophenyl, acetylaminophenyl, alpha and beta naphthyl and the like or an aralkyl radical such as benzyl, phenylethyl, tolylethyl, chlorophenylethyl and the like.

5 If so desired, other than primary amines may be utilized. The product will be an —N—N—dipyrrolidine, in part, together with mixed side reaction products.

The ring closure step may be modified in accordance with certain circumstances. For example, in the case of certain liquid amines, the other constituents may be soluble therein, or sufficiently soluble to permit reaction without any added solvent. This may be illustrated by the 15 following typical example.

EXAMPLE 3

Methyl ester of 1-phenylpyrrolidine-2,5-dicarboxylic acid

20

Freshly distilled aniline and meso methyl alpha,delta-dibromoadipate, in the mole ratio of about 3.5:1, are combined in a flask and heated 25 under reflux until reaction is substantially completed. The oily solid residue is poured into 6 N hydrochloric acid and extracted three times with ether. The ether extracts are combined, washed with water, dried over anhydrous calcium sulfate, filtered and the ether removed by distillation. The crude ester is purified by distillation at 27 mm. The desired ester is obtained as a light yellow oil in the fraction distilling at 220-230° C. in about 68% yield. Crystallization 35 starts almost immediately but is complete only after long standing. Recrystallized from 95% ethyl alcohol, the ethyl is obtained as large transparent colorless prisms melting at 88° C.

On the other hand, a suitable solvent may be found highly advantageous. Particularly is this true of the alkyl and substituted alkyl amines. For the purpose, dry benzene is excellent. Other solvents which may be utilized, if so desired, include chloroform and absolute ethyl alcohol. This procedure is illustrated in the following example.

EXAMPLE 4

1-butyl-2,5-dicarbethoxypyrrrolidine

Freshly distilled n-butylamine and ethyl alpha,delta-dibromoadipate, in the mole ratio of about 3:1 are admixed with sufficient dry benzene to form a clear solution. In about 10 minutes the mixture heats spontaneously nearly to the boiling point and shortly thereafter crystals of n-butylamine hydrobromide begin to form. The mixture is allowed to stand until heating ceases and is then heated under reflux until re-

action is substantially complete. A small amount of ether is added and the salt filtered off and washed with ether. The filtrate is extracted with 6 N sulphuric acid in several successive extractions and the acid extract neutralized with sodium carbonate. The oil which separates is taken up in ether. The aqueous solution is further extracted with ether. The ether extracts are combined, dried, the ether removed and the residue distilled at about 1-2 mm. A small fraction is taken off at about 120-125° C. and a larger fraction at 125.5-130° C. The product is purified by redistillation at 155-156° C. and has a N_{D}^{20} of 1.4514.

Carrying out the reactions directly as in the preceding Examples 3 and 4, produces fairly high yields, in some cases as high as 60-65% of the theoretical. Generally speaking, however, the yields are lower than is generally desirable. In accordance with the present invention, it has been found that the cyclization can be catalyzed by the presence of a small amount of potassium iodide. In so doing, the over-all yields may be raised from a third to as much as a half. A good illustrative use of this procedure is given in the following example.

EXAMPLE 5

Ethyl 1-phenylpyrrolidine-2,5-dicarboxylate

327 parts of freshly distilled aniline, 360 parts of meso ethyl alpha,delta-dibromo adipate and 5 parts of dry powdered potassium iodide are combined in a flask equipped for reflux. On gentle warming, spontaneous reaction starts and crystals appear almost immediately. After somewhat violent reaction has subsided, an oily pale orange crystalline mass is obtained. The mass is heated at about 85-90° C. until reaction is substantially complete. The reaction product is suspended in 6 N hydrochloric acid and then extracted three times with ether. Combined ether extracts are washed, dried and filtered. The ether is removed by distillation and the desired ester obtained by distillation of the oil at 2 mm. collecting a fraction which distills at 168-169° C. The yield is 254 parts or about 90% of theory. The ester is a pale yellow nearly colorless liquid $N_{D}^{21.5}$ 1.5230 boiling at 144° C. at 0.5 mm. The advantage of using the potassium iodide is illustrated in repeating the experiment omitting the iodide. The ester produced is the same but the yield is only 61% of theoretical.

It is also to be noted from the reaction that for each mol of amine utilized in the reaction, two mols of hydrobromic acid are released. For that reason, in preparing the reaction mixture for the above examples, an excess of amine has been provided to serve as an acceptor for the HBr. For complete reaction at least three mols of amine are required for each mol of adipate. Usually, an additional slight excess is found to be helpful. So prepared, a good practice is to utilize an amine-adipate ratio of from about 3:1 to 3.5:1.

These ratios are not objectionable with readily available amines. In some cases, however, the available amount of amine may render the use of such high amine-adipate ratios objectionable. In those cases, an alternative procedure is to provide an extraneous agent to accept or neutralize the HBr. Basic secondary or tertiary amines tend to cleave the bromoester. In accordance with the present invention, it has been found that any suitable salt, such as an alkali metal salt of a weak acid, may be used to neutralize the HBr. Sodium and potassium car-

bonate were found suitable for the purpose. This practice may be illustrated by the following examples.

EXAMPLE 6

1-cyclohexyl-2,5-dicarbethoxypyrrrolidine

Thirty parts (.083 mol) of ethyl alpha,delta-dibromo adipate, twenty-five parts (.25 mol) of freshly redistilled cyclohexylamine, one part of pulverized potassium iodide and seventy-five parts of dry benzene are admixed, allowed to stand for several hours and refluxed until reaction appears complete. After cooling, the reacted mixture is filtered to remove the insoluble cyclohexylamine hydrobromide. 29.5 parts or 98% of theoretical are obtained. The filtrate is extracted with 70 ml. of 6 N sulphuric acid in three portions and the acid extract is, neutralized the solid sodium carbonate. An oil separates which is taken up in ether and the aqueous phase is extracted with ether. The combined ether extracts are dried, the ether removed by distillation and the residue distilled at about 1 mm. pressure. 21.2 parts of colorless oil boiling at 133° C. and having a N_{D}^{20} of 1.4742 are obtained. This is equivalent to a yield of about 85.5% of theory. A sample, redistilled for analysis, had a N_{D}^{20} of 1.4738 and was found to have a nitrogen content of 4.62% as compared with the 4.71% of theory.

EXAMPLE 7

1-cyclohexyl-2,5-dicarbethoxypyrrrolidine (Potassium carbonate method)

Example 6 was repeated using equimolecular parts of ethyl alpha,delta-dibromo adipate, cyclohexylamine and pulverized anhydrous potassium carbonate. A small amount of pulverized potassium iodide was also added. After nine hours of reaction time, the product was isolated as in Example 6 yielding 50% of theory of a product boiling about 133° C. having a N_{D}^{20} of 1.4742, identical with the distillate in Example 6.

EXAMPLE 8

1-cyclohexyl-2,5-dicarbethoxypyrrrolidine

Example 7 was repeated extending the reaction time to 52 hours. The product isolated was identical with that in Examples 6 and 7. The yield, however, was 54% of theory.

From the foregoing examples, it will be seen that the potassium carbonate method does not yield as high a quantitative product in a single operation as can be expected from the use of an amine-adipate ratio of 3:1. However, the yields are much better on the basis of the mols of amine consumed.

By the above outlined procedures, cyclization is readily accomplished to produce the various substituted dialkyl esters of N-substituted pyrrolidine, 2,5-dicarboxylic acids in which the N-substituent has the various values outlined. Typical products so prepared are shown in the following table.

TABLE I

1-substituted-2,5-dicarbethoxypyrrrolidines

Having accomplished the ring-closing operation of the present process, in accordance with the foregoing procedure, the dicarbalkoxy pyrrolidine is ready for the second step. In general, in the present process, this comprises reacting the pyrrolidine ester with an amino alcohol in the presence of a metal alcoholate as a catalyst, whereby an ester substitution is accomplished. In the present process the alkanol corresponding to the alkyl radical in the adipic ester is one of the reaction products and must be removed. Distillation may be employed after the reaction has been completed. However, there is usually an advantage in removing the alcohol during the reaction as this increases the reaction rate. When continuous distillation is employed, the alkyl of the adipate should be an alcohol having a boiling point suitable for continuous distillation from the reaction mixture at the reaction temperature. The distillation may take place either at atmospheric or reduced pressure.

The process of the present invention is generally applicable to monohydric aminoalcohols having a tertiary amino group. These may be represented by the formula:

in which R is an aliphatic hydrocarbon residue of 1-3 carbon atoms and R₁ and R₂ are the same straight chain alkyl radicals or form with the nitrogen atom a heterocyclic ring such as the piperidine or morpholine ring. The most important amino alcohols from a practical standpoint are those in which R is a straight saturated chain which may be represented by the formula:

in which n is a small whole number from 1-3 and where R has 1-3 carbon atoms.

Typical illustrations of the amino alcohols which may be used in the present invention are dimethylaminomethanol, dimethylaminoethanol, diethylaminoethanol, dipropylaminoethanol, diethylaminopropanol, dipropylaminopropanol, methylethylaminopropanol, piperidinoethanol, morpholinoethanol, methylethylaminoethanol and the like.

The choice of the particular alcohol and acid used depends upon the product to be produced. Variations in the acid or alcohol do not affect the present reaction except as to the extent to which the reaction may be carried to completion in a reasonable time and therefore the quantity of the product practically obtainable. The temperature at which the reaction is carried out may be varied in accordance with the particular reagents selected.

In accomplishing our process, the use of a metal alcoholate is very important, apparently being principally responsible for the superior yields obtained. It also appears to increase the rate of reaction. The metal alcoholate may be added to the reaction mixture as a preformed alcoholate or as a strongly basic metal which will form the alcoholate in situ. The particular metal alcoholate which is used is not so important.

Metallic sodium is easily available, relatively cheap, and since it forms the alcoholate in the reaction mixture, produces very satisfactory results. Other alkali metals and alloys, for example, potassium, give similar results but usually do not justify the added cost. Similar results may also be obtained with metal amides such as sodamide. It is an additional advantage of the present invention that the amount of the metal alcoholate present in the reaction as well as its nature is not critical, and it may be used in various proportions throughout a considerable range. The optimum amounts, however, will vary somewhat with different alkamine esters to be produced.

In the alcoholysis one feature, as shown in these examples, should be noted. Theoretical requirements for the reaction would be for at least two molecular proportions of the amino alcohol for each mol of the adipic ester consumed.

Experience has shown that a large excess of the amino alcohol is of considerable benefit. The reaction operates best with two to three times or more the theoretical considered amount of amino alcohol.

While it is an advantage of the present invention that this excess is not lost but may be recovered and reused, nevertheless, it is inconvenient to use an excess larger than necessary. It has been found that a good average practice is to employ about five times the theoretically required amount. For this reason, as much more than the five proportions as may be desired may be used, but there is no particular advantage in so doing.

The alcoholysis will be illustrated by the following examples. Again, these examples are taken as illustrative only and not by way of limitation.

EXAMPLE 9

Di-(beta-diethylaminoethyl) ester of 1-methylpyrrolidine-2,5-dicarboxylic acid

Fifty-three parts of 1-methyl-2,5-dicarbethoxypyrrrolidine and two hundred fifty parts of beta-diethylaminoethanol, in which one part of metallic sodium was dissolved, are placed in a reaction vessel equipped with distillation apparatus. The mixture is heated at about 160°-170° C., until reaction is substantially complete, care being taken to prevent distillation of amino alcohol. The excess amino alcohol is then removed

at reduced pressure and the residue is taken up in ether and sufficient water to dissolve all the material. The ether layer is removed and the water phase extracted twice with ether, the ether extracts being combined, dried and ether distilled therefrom. The residue is purified by distillation at about one mm. pressure, yielding about 41% of theory of the amino ester having a boiling point at about one mm. of 172°-181° C., and having a N_D^{20} of 1.4690.

Repeating Example 12 but substituting sixty-five parts of 1-cyclohexyl-2,5-dicarbethoxypyrrrolidine for the pyrrolidine of that example yielded about 60% of theory of a yellow oil boiling at 188°-197° C. at 1 mm. from a heating bath at 225°-230° C. having a N_D^{20} of 1.4805. A sample fractionated therefrom at 203°-204° C. at 1 mm. from a bath at 235° C. had the slightly lower N_D^{20} of 1.4803.

EXAMPLE 14

The di-(beta-morpholinoethyl) ester of 1-butylpyrrolidine-2,5-dicarboxylic acid

EXAMPLE 10

Di-(beta-diethylaminoethyl) ester of 1-ethyl-pyrrolidine-2,5-dicarboxylic acid

Substituting 60 parts of 1-ethyl-2,5-dicarbethoxy-pyrrolidine for the 1-methyl-2,5-dicarbethoxypyrrrolidine of Example 9, yielded the amino ester boiling at 168°-170° C., having a N_D^{20} of 1.4675. A further fraction taken therefrom boiled at 168.5°-169° C. at about 1 mm. pressure with a heating bath at 205° C. The product had a N_D^{20} of 1.4678.

EXAMPLE 11

Hydrochloride di-(beta-diethylaminoethyl) ester of 1-ethyl-pyrrolidine-2,5-dicarboxylic acid

Example 10 was repeated. After the reaction product was taken up in the combined ether extracts, the hydrochloride salt was precipitated by the addition of anhydrous hydrogen chloride in absolute ether, the precipitated salt was recovered. It proved to be so hygroscopic the melting point determinations proved substantially meaningless as a means of identification. This was found to be a common characteristic of the hydrochlorides of the esters subsequently prepared.

EXAMPLE 12

Di-(gamma-diethylaminopropyl) ester of 1-butylpyrrolidine-2,5-dicarboxylic acid

Repeating Example 9 substituting eighty-five parts of 1-butyl-2,5-dicarbethoxypyrrrolidine for the 1-methyl-2,5-dicarbethoxypyrrrolidine of Example 9 and 610 parts of gamma-diethylaminopropanol for the beta-diethylaminopropanol, gave a distillate boiling at 173°-176° C. at about 0.5 mm. from a heating bath at 200°-210° C. The N_D^{20} was 1.4619. A fraction redistilled therefrom boiling at 186° C. at 1 mm. from a heating bath at 210° C. had the same N_D^{20} .

EXAMPLE 13

Di-(gamma-diethylaminopropyl) ester of 1-cyclohexylpyrrolidine-2,5-dicarboxylic acid

EXAMPLE 17

The di-(beta-diethylaminoethyl) ester of 1-(p-tolyl)-pyrrolidine-2,5-dicarboxylic acid

Six hundred forty-seven parts of freshly dis-

11

tilled beta-diethylaminoethanol in which 1½ parts of sodium is dissolved are combined with one hundred twenty-five parts of 1-(p-tolyl)2,5-carbethoxypyrrolidine and the mixture treated as in the preceding example. The light yellow oil distilling at 0.5 to 1 mm. from 175°-185° C. on redistillation, boiled at 175°-178° C. at 0.5 mm. had an $N_D^{21.5}$ of 1.5144.

EXAMPLE 18

The di-(beta-diethylaminoethyl) ester of 1-(2,4-dimethylphenyl)-pyrrolidine-2,5-dicarboxylic acid

Substituting about one hundred five parts of 1-(2,4-dimethylphenyl)-2,5-carbethoxypyrrolidine for the pyrrolidine used in the preceding example and proceeding with the same general procedure, yielded an ether extract containing the alkamine ester. To this extract a slight excess of dry hydrochloride in dry ether is added. The hydrochloride of the alkamine ester precipitates as a light tan amorphous solid. This solid has better physical properties than most of the hydrochloride salts prepared in accordance with the present invention but is so hygroscopic that purification by recrystallization is impractical as was found true of most of the amino esters. Accordingly, the solid hydrochloride is taken up in water and the free base liberated with aqueous potassium hydroxide, alkali being added to a weakly alkaline pH of approximately 8. The free base is taken up in ether, washed, dried and recovered as in the preceding examples. Distillation yields a purified product boiling at 187°-190° C. at 1 mm. having a $N_D^{21.5}$ of 1.5023.

Using the procedure illustrated by the above examples, substantially any of the described alkamine esters can be produced. Other illustrative dialkamine esters as prepared include, for example, the di(beta-diethylaminoethyl) esters of 1-(R)-2,5-dicarbethoxypyrrolidines shown in the following table.

TABLE II

R	Boiling Point		N_D^{20}

¹ $N_D^{21.5}$

The dialkamine esters have various physiological activity in and of themselves. Several of these

12

compounds have notable activity as local anaesthetics. Many of them have marked impressive effect on the blood pressure. A number of them are active as antispasmodics, some of the latter being selective to the longitudinal muscle in direct spasm and having a marked parasympathetic accompanying effect. The particular benefits in use depending upon the particular R-substituent of the particular amino-alcohol chosen as noted above. However, their principal utility is as intermediates in the preparation of other compounds which themselves are not part of the present invention.

We claim:

1. Alkamine esters of an N-substituted pyrrolidine carboxylic acid of the type formula

in which R is a radical selected from the group consisting of the alkyl radicals of 1-6 carbon atoms, cycloaliphatic radicals of 6-8 carbon atoms, aryl radicals of 6-8 and 10 carbon atoms, and aralkyl radicals of 7-9 carbon atoms; and Alk is the alkamine radical of a tertiary amino monohydric alcohol.

2. An alkamine ester according to claim 1 in which Alk is the radical

wherein x is an integer from 1-3 and y is an integer from 0-3.

3. Alkamine esters according to claim 2 in which R is an aralkyl radical of 7-9 carbon atoms.

4. Alkamine esters according to claim 2 in which R is an aryl radical of 6-8 and 10 carbon atoms.

5. Alkamine esters according to claim 2 in which R is cyclohexyl.
